WILLIAM H. SELLARS, OF EAST MILTON, MASSACHUSETTS

LATCH

Application filed June 7, 1927. Serial No. 197,032.

My present invention relates to latches, and more particularly to latches of the type adaptable for automobile doors and the like. My present novel latch is particularly adapted for use in automobile doors of the "steel body" type, wherein essential features of a latch should include compactness, room for raising and lowering of the door window, and ruggedness of construction. My present latch possesses all of these essential features.

A further feature of the present invention resides in a novel handle mechanism which will simultaneously unlatch the latch and open the door, in combination with means operated internally of the automobile to lock or unlatch the mechanism from said interior.

My present novel latch, when utilized on wooden doors, requires the cutting away of but a relatively small portion of the wood 20 of the door and frame, in obvious contrast with prior locks or latches, which require excessive recesses in the wood of the door and frame, thus weakening the construction at a most vital point.

In my present novel latch, I preferably utilize a vertical bolt, or latch, rather than the usual horizontal bolt, since a vertical bolt may readily be constructed and arranged for cooperation with a frame-carried toothed 25 plate to yield relatively to the toothed plate without possibility of damage even with the sagging that sometimes takes place with the usual construction of door supporting means.

Associated with the vertically movable bolt 30 is a door guiding and lifting means comprising a toothed plate adapted to be secured to the door jamb and having an upwardly facing tooth with which the bolt may engage to hold the door in closed position. Conveniently, the toothed plate is provided with a cam-shaped plate with which there is arranged 35 to co-operate a supporting lug adapted to be carried by the door, the supporting lug and the last-named plate constituting the door guiding and lifting means. Since the supporting 40 lug bears a definite relationship to the bolt when in its latching engagement with the toothed plate, the lug and plate serve to position the bolt for full depth engagement 45 with a selected tooth on the toothed plate.

By providing the handle mechanism above described, the double action at present required to open an automobile door is eliminated, a single movement of the outside handle simultaneously releasing the latch and causing the door to be swung open. This feature will be appreciated by the public generally, and automobile owners particularly, due to the simplicity and ease of operation.

Another feature of importance resides in 55 the provision of an inside handle, operating a horizontally slidable bar, movable, at the will of the operator, into several different and distinct positions. When in one of these positions, the said bar will effectually lock the 60 latch, preventing raising of the same from the outside, and thus insuring locking of the door. When in another of the positions referred to, the bar may be said to be in neutral position, 65 neither locking the latch against vertical 70 movement, nor performing any function in and of itself. When moved to still another of its optional positions, the said bar will operate upon the latch, raising same from its ratchet plate, and permitting opening of 75 the door from the interior.

In all of these positions the said horizontal bar is held under spring tension, which will prevent rattling or looseness thereof.

I believe that the latch mechanism above 80 described is novel, and I have therefore claimed the same broadly herein.

These and other features of the invention and combinations of parts will be hereinafter 85 more fully pointed out and claimed.

Referring to the drawings, illustrating a preferred embodiment of the present invention,

Fig. 1 is a front elevation, in fragmentary detail, of an automobile door with my latch 90 attached;

Fig. 2 is an end elevation of the door portion containing my latch;

Fig. 3 is a top plan view of the door and latch together with a portion of the pillar or 95 frame;

Fig. 4 is a perspective view of the ratchet plate;

Fig. 5 is a front elevation, partly broken 100 away, of the latch; and

Fig. 6 is a cross sectional view on the line 6-6 of Fig. 3.

As shown in the drawings, 1 indicates the frame of a door, here illustrated as an automobile door, and 2 designates the body pillar or stanchion.

The latch itself comprises a back plate 3, and front casing member 4 having its edges turned inwardly toward the back plate 3, as 10 illustrated at 5. Secured to the frame of the door is a plate 6, jogged at 7, 7 to fit the body pillar or stanchion. Vertically movable within in the latch casing is a latch plate 8 having a bolt or latch 9 preferably formed as an integral part thereof. A lug 10 is provided on the plate 8, and between the lug 10 and top wall or side 5 is a rod or shaft 11, surrounding which is a coiled spring 12, this spring 15 abutting at its lower end on the lug 10 and at its upper end on the inside of the upper wall 5. The function of this spring 12 is to retain the plate 8, and hence the latch or bolt 9, in lower position. When in this position the latch 9 rests in one of the teeth of a ratchet 20 25 13 adapted to be secured to the door jamb, as clearly shown in Fig. 2. At predetermined portions the casing 4 has inturned webs, or ears, as shown at 14, which insure movement of the plate 8 in a vertical direction, acting 30 as guides therefor. To the outside of the door is affixed a plate 15, having a yoke or arms 16 extending inwardly of the door, and provided with a pin 17 spanning said arms adjacent to their inner ends. A handle 18 has a 35 reduced portion 19 extending through a slot 20 in the plate 15, which reduced portion is pivoted on the pin 17, and has a cam face 21. The plate 15 is secured to the door 1 by screws 22. Pivoted to the plate 6 is a bell crank lever 40 45 23 having a hub 24 and reduced portion or cam follower 25, which follower 25 is engaged by the cam face 21 of the handle 18. This bell crank lever 23 has a pivot point 26, and at the end opposite the cam follower 25 is provided with an arm or boss 27.

An inspection of Fig. 6 will readily illustrate the method of operation of the latch by the outside handle. When the handle 18 is pulled away from the door, this causes depression 50 55 of the cam follower 25, pivotal movement of the bell crank lever on its pivot 26, and raising of the arm 27 vertically. This vertical movement will cause the arm 27 to engage the lug 28 on the plate 8, raising the plate 8 vertically, and hence causing vertical movement of the latch 9 out of engagement with the ratchet 13, and will also cause opening of the door, since the pull on the handle tends to swing the door on its hinges, thereby accomplishing the double function of releasing the latch and opening the door by a single movement. When the plate 8 is unaffected by the handle, the spring 12 will maintain the latch 9 in engagement with the ratchet 13, so that 60 65 the door is securely latched. As a further fea-

ture of importance I provide a door lifting and supporting lug 29, which engages a supporting plate 30, preferably formed as an integral part of the ratchet 13. The forward end of the plate 30 is cam shaped or curved, as 70 illustrated at 31, so that, should there be any sag in the door when open, on closing the same the lug 29 will engage the curved face 31, and will ride thereon, raising the door until, when completely closed, the supported lug is resting on the flat surface of the plate 30. As 75 shown in Fig. 6, the walls 5 of the casing 4 penetrate through the back wall 3 of the latch, and are clinched over as shown at 32 to clamp the casing 4 to the back plate 3. 80

To control the locking and unlatching of the mechanism internally of the automobile, I provide an inside handle operated locking, unlocking and unlatching bar 33, provided with detents or notches 34 and 34a, in 85 its lower edge. Webs 35 of the casing 4 provide guides for this bar 33, to provide for true horizontal reciprocation thereof. On this bar 33 is carried a small plate 36 having a nose or toe 37. Adapted to engage the notches 34 is a spring 38 having a V-shaped end 39, and secured to the casing member 3 at 40, the tension of this spring being upward. The end of the bar 33 is formed U-shaped, as shown at 41, a portion 42 of the bar being cut out and bent, to complete the U formation. Engaging the U end 41 of the bar 33 is an eccentric portion 43 of an inside handle rod 44, operated by the inside handle 45. In Fig. 5, the bar 33 is 90 illustrated as in locking position, the toe 37 engaging the top of the arm 27, and effectively preventing raising thereof, and hence preventing raising of the latch 9 out of the ratchet 13. The casing 4 is bent inwardly 100 throughout a portion of the length of the bar 33, as illustrated at 46, to act as a retaining element for said bar to insure tightness thereof, thus preventing rattling sounds. When in locked position, the end 105 39 of the spring 38 engages the notch 34a, so the vibration or road shocks will not dislodge the toe 37 from locked position. When it is desired to move the bar 33 to unlocked or neutral position, the inside handle 45 is 110 partially turned, rotating the eccentric portion 43 of the rod 44 through a portion of its arc of rotation, until the end 39 of the spring 38 engages the notch 34 in which position the toe 37 will be freed from the arm 27, permitting the raising of the latch by the outside handle 18. The action of the spring 38 on the notch 34 will also prevent sliding or slipping of the bar 33 back into locking position. 115 120 125

When it is desired to open the door from the interior, the handle 45 is still further rotated, causing rotation of the eccentric 43 in the U end 41 of the bar 33, and drawing the bar 33 to the right. The plate 36 is pro- 130

vided with an inclined or cam face 47, and the latch plate 8 is provided with a lug or cam follower 48, having inclined faces 49, with which will engage the cam face 47 of the plate 36, upon movement of the latter to the right in Fig. 5, causing the lug 48 to ride up on the inclined face 47 thus raising the latch plate 8 and latch 9, disengaging the latch from the ratchet 13, and permitting the door to be pushed open from the interior. On releasing the handle 45, the downward action of the spring 12 will cause the downward movement of the latch plate 8, also movement of the plate 37 to the left (Fig. 5) by reason of the action of the lug 48 on the inclined edge 47, and returning of the latch 9 to normal position.

It will thus be appreciated that I have devised an extremely simple latch mechanism, consisting of a minimum of parts, and yet resulting in an extremely efficient structure. Such a latch is economical to manufacture, simple of assembly, and easy of application to a door and body structure.

25 The inside operated bar 33 is normally left in neutral position, viz., with the V end 39 engaging the notch 34, so that the lock is in condition for unlatching externally thereof. When in this position, a single pull 80 of the handle 18 will cause the arm 27 to engage the lug 28 and raise the bolt 9 out of engagement with the ratchet 13, simultaneously causing opening of the door, due to the pull on the handle 18.

35 While I have illustrated the handle 18 as being in position to be pulled downwardly, it will be appreciated that I may vary this position of the handle, and may arrange same to be pulled sidewise, which will accomplish the same result, in as simple a manner as that herein illustrated. The position and arrangement of the handle 18, in a vertical position, as shown herein, is preferable, due to the fact that in this position the handle is not as likely to catch the sleeves or clothing of the wearer when approaching or passing the handle, which is a disadvantage found in present handles.

When leaving the car for a period of time, 50 and desiring to lock the same, the inside handle 45 is rotated a sufficient distance to force the bar 33 to the left, as shown in Fig. 5, until the toe 37 rides over the top of the arm 27, thus effectually preventing opening 55 of the door from the outside. This arrangement of latch is of course suitable for all of the doors of an automobile except the one which is locked from the outside, and on which door I can utilize any desirable 60 type of lock, preferably a key operated lock, the other doors being unlocked after entering the car.

It will thus be seen that I have devised a desirable lock of this type, and one which 65 contains many novel features and elements,

and I have therefore claimed these features and elements broadly herein.

Because of the construction of the bell crank lever 23, and its position in contact with the end plate 6, ample room is left for 70 the raising and lowering of the window 50, and thus the application of my novel latch to an automobile door will not interfere with the housing of the window 50 in the lower portion of the door, when the window is 75 lowered or opened.

While I have necessarily described my present invention by reference to details of the illustrated construction, it will be appreciated that I may vary the size and shape 80 and the construction and arrangement of parts within reasonably wide limits without departing from the spirit of the invention.

My invention is further described and defined in the form of claims as follows:— 85

1. Latch mechanism of the kind described, comprising a bolt disposed at one side of a door, a handle disposed at the opposite side of said door, a member pivoted between its ends and forming an operating connection 90 between said handle and bolt, and means to prevent movement of said member.

2. Latch mechanism of the kind described, comprising a bolt disposed at one side of a door, a handle disposed at the opposite side 95 of said door, a member pivoted between its ends and forming an operating connection between said handle and bolt, and means operative from the bolt side of the door to prevent movement of said member. 100

3. Latch mechanism of the kind described, comprising a bolt disposed at one side of a door, a handle disposed at the opposite side of said door, a bellcrank lever pivoted between its ends and forming an operating connection between said handle and bolt, means operative from the bolt side of the door to prevent movement of said lever, and a spring adapted to hold said means in adjusted position. 105

4. Latch mechanism of the kind described, comprising a bolt disposed at one side of a door, a handle disposed at the opposite side of said door, a bellcrank lever pivoted between its ends and forming an operating connection between said handle and bolt, and means operative from the bolt side of the door to prevent movement of said lever, said last named means being also arranged to operate said bolt. 110

5. Latch mechanism of the kind described, comprising a vertically movable bolt disposed at one side of a door, a handle disposed at the opposite side of said door, a bellcrank lever pivoted between its ends and forming an operating connection between said handle and bolt, and means operative from the bolt side of the door to prevent movement of said lever, said last named 125 130

means being also arranged to operate said bolt.

6. Latch mechanism of the kind described, comprising a vertically movable bolt disposed at one side of a door, means to normally retain said bolt in lowered position, a handle disposed at the opposite side of said door, a bellcrank lever pivoted between its ends and forming an operating connection between 10 said handle and bolt, and means operative from the bolt side of the door to prevent movement of said lever, said last named means being also arranged to operate said bolt.

15 7. Latch mechanism of the kind described, comprising a bolt disposed at one side of a door, a handle disposed on the opposite side of said door, a lever pivoted between its ends, an arm on one end of said lever engaging said bolt, a projection on the opposite end of said lever engaging said handle, and a bar operable from the bolt side of the door to engage the arm of said lever to prevent movement thereof.

25 8. Latch mechanism of the kind described, comprising a bolt disposed at one side of a door, a handle disposed on the opposite side of said door, a lever pivoted between its ends, an arm on one end of said lever engaging said bolt, a projection on the opposite end of said lever engaging said handle, a bar operable from the bolt side of the door to engage the arm of said lever to prevent movement thereof, and a spring adapted to hold said bar in 35 adjusted position.

9. Latch mechanism of the kind described, comprising a vertically movable bolt disposed at one side of a door, a horizontally disposed ratchet plate cooperating with said locking 40 bolt, a handle disposed on the opposite side of said door, a lever pivoted between its ends, an arm on one end of said lever engaging said bolt, and a projection on the opposite end of said lever engaging said handle.

45 10. Latch mechanism of the kind described, comprising a vertically movable bolt disposed at one side of a door, a horizontally disposed ratchet plate cooperating with said locking bolt, a handle disposed on the opposite side of said door, a lever pivoted between its ends, an arm on one end of said lever engaging said bolt, a projection on the opposite end of said lever engaging said handle, a bar operable from the bolt side of 50 the door to engage the arm of said lever and prevent movement thereof, and guiding means for said bolt and said bar.

11. Latch mechanism of the kind described, comprising a bolt disposed at one 55 side of a door, a handle disposed on the opposite side of said door, a lever pivoted between its ends, an arm on one end of said lever engaging said bolt, a projection on the opposite end of said lever engaging said handle, a bar to engage the arm of said lever

to prevent movement thereof, and means operable from the bolt side of said door to control the movement of said bar.

12. Latch mechanism of the kind described, comprising a bolt disposed at one 70 side of a door, a handle for operating the bolt, a ratchet plate secured to the door jamb with which the bolt cooperates in latching the door, a member associated with the ratchet plate, and a member on the door adapted 75 to contact with the first mentioned member to lift the door and to support it in position for most effective cooperation of the bolt and ratchet plate.

13. Latch mechanism for an automobile door, comprising a vertically movable bolt adapted to be disposed at one side of a door, a ratchet plate adapted to be secured to the door jamb of the car for cooperation with the bolt in latching the door, a cam member formed integrally with the ratchet plate, and a member adapted to be carried by the car door in definite spaced relation to the bolt when the latter is in its lowest position and arranged for cooperation with the cam member to lift a sagging door and to support the door when in closed position with the bolt in full depth engagement with the ratchet plate.

14. In a latch mechanism for automobile 95 doors, a bolt mounted upon one side of a door for vertically sliding movement thereon, a handle for operating the bolt, a toothed member adapted to be secured to the door jamb and to be engaged by the bolt to hold 100 the door in closed position, said toothed member having an upwardly facing surface, and a member spaced in predetermined relation to the bolt when the latter is in its lowermost position and adapted for engagement with 105 the upwardly facing surface of the toothed member for guiding and supporting the door during closing thereof.

15. In a latch mechanism for automobile 110 doors, a latch adapted to be mounted for vertically sliding movement upon the inside of a door, said latch having a projecting bolt portion, a handle for operating the latch and bolt, a plate adapted to be secured to a door jamb and having an upwardly facing surface and an upwardly facing tooth adapted 115 to be engaged by the bolt, and a member adapted to be secured to the door in definite spaced relation to the bolt when in its tooth engaging position and arranged for engagement with the upwardly facing surface of the toothed plate to support the door and to insure proper engagement of the bolt with the tooth of the plate.

16. In a latch mechanism for automobile 125 doors, a latch adapted to be mounted for vertically sliding movement upon one side of a door, said latch having a projecting bolt portion, a handle for operating the bolt, a ratchet plate adapted to be secured to a door 130

jamb, said ratchet plate having an upwardly facing surface and upwardly facing teeth adapted to be engaged by the bolt, and a member adapted to be secured to the door in 5 predetermined spaced relation to the bolt when the latter is in its lowermost position and arranged for engagement with the upwardly facing surface of the ratchet plate to support the door and to insure proper engagement of the latch with a selected tooth 10 of the ratchet plate.

In testimony whereof, I have signed my name to this specification.

MINAS H. KASHIAN.
